Primary Examiner — Keith J Wilson(74) *Attorney, Agent, or Firm* — Foley & Lardner LLP(57) **CLAIM**

I claim the ornamental design for a shower head, as shown and described.

DESCRIPTION

FIG. 1 is a top, front perspective view of an embodiment of the claimed design;

FIG. 2 is a front elevation view thereof;

FIG. 3 is a right side elevation view thereof, the left side elevation view being a mirror image thereof;

FIG. 4 is a rear elevation view thereof;

FIG. 5 is a bottom, rear perspective view thereof;

FIG. 6 is a top, front perspective view of another embodiment of the claimed design;

FIG. 7 is a front elevation view thereof;

FIG. 8 is a right side elevation view thereof, the left side elevation view being a mirror image thereof;

FIG. 9 is a rear elevation view thereof; and,

FIG. 10 is a bottom, rear perspective view thereof.

The ornamental design which is claimed is shown in solid lines in the drawings. The broken lines in the drawings are for illustrative purposes only and form no part of the claimed design.

1 Claim, 10 Drawing Sheets(56)
